UNITED STATES PATENT OFFICE.

GEORGE H. GILMAN, OF BOSTON, MASSACHUSETTS, ASSIGNOR TO SULLIVAN MACHINERY COMPANY, A CORPORATION OF MASSACHUSETTS.

HAMMER DRILL.

Application filed March 25, 1916, Serial No. 86,814. Renewed February 21, 1923.

To all whom it may concern:

Be it known that I, GEORGE H. GILMAN, a citizen of the United States, residing at Boston, in the county of Suffolk and State of Massachusetts, have invented certain new and useful Improvements in Hammer Drills, of which the following is a full, clear, and exact specification.

My invention relates to hammer drills.

It has heretofore been proposed to provide a resiliently mounted stop for limiting the forward movement of the steels used in such drills, a stop of the character referred to being shown in my Patent No. 1,126,628, January 26, 1915. In the use of such a device, however, it has been found that when withdrawing a steel, the hammer is sometimes unable to strike the end of the steel when the latter is in its extreme forward position, i. e. with its shoulder or collar resting against the stop, considerable difficulty having accordingly been experienced with stuck steels.

My invention has for its object to release a stuck drill steel in an improved manner. A more specific object of my invention is to provide improved means whereby the steel may be maintained within the path of the hammer as the steel is withdrawn from a hole, in such a manner that the hammer may be made to act upon the rear end of the steel at any time and thereby cause the dislodgement or crumbling of the substance or substances engaging the steel and preventing the latter from being withdrawn.

In the accompanying drawings, I have for purposes of illustration shown one embodiment which my invention may assume in practice.

In these drawings,—

Figure 1 is a plan view partially in section, of a hammer drill equipped with my improvement.

Figure 2 is an enlarged detail view of a portion of the mechanism shown in Figure 1, the steel engaging member being shown in operative and inoperative position.

Figure 3 is an end view of the steel engaging member in operative position, the same being shown as seen from the left in Figures 1 and 2.

Figure 4 is a detail view of the end of the chuck.

The hammer drill may be of any known or standard construction, so that the same

need not be specifically described herein more than to say that it comprises the usual front and rear cylinder heads 1 and 2 having the cylinder 3 disposed between the same, and that in this cylinder moves a piston having preferably a reduced hammer portion 4 movable through a rotatable or stationary chuck 5, into engagement with the end of the steel 6, which, of course, extends outward through a suitable opening 7 in the end of the chuck.

In my improvement, means are provided whereby the drill steel 6, while being withdrawn from a hole, may be retained within range of the hammer portion 4 of the piston so that, instead of the hammer operating uselessly without striking the steel, as is the case with the stop heretofore used, when the steel is in its extreme forward position the hammer may continue to strike on the end of the steel. In carrying out my improvement, these means preferably cooperate with a projection or suitable annular collar 8, such, for instance, as is usually provided on a steel, and through their engagement with that projection or collar, force the steel back into the chuck and retain it in such a position therein that it is within striking range of the hammer. In the embodiment of my invention shown herein, they assume the form of a yoke 9 through which the steel is reciprocable, the yoke being adapted to fit over the shank of the drill a slight distance in front of the collar 8 when the latter engages the chuck, and having rearwardly extending arms 10 pivotally mounted on the drill and disposed on opposite sides of the chuck 5. As shown, these arms are provided with lateral cylindrical extensions 11 at their rear ends, and these extensions are in turn provided with longitudinally extending oppositely tapered communicating openings 12 therein, through which extend suitable longitudinally disposed rods 13. These rods 13 are preferably, though not necessarily, the side rods of the drill which extend between the front and rear heads thereof, although other suitable rods may be employed if desired. As shown, these rods, in turn, carry on their front ends, coiled springs 14 normally holding the yoke against the collar 8 and acting between suitable nuts 15 and buffers 16, the latter in this instance preferably being provided with suitable arcuate recesses 17 having beveled ends 18 so

that the buffers may seat against the extensions 11 and yet permit ready movement of these extensions as the yoke 9 is turned about the rods 12 as a pivot in its movement from its inoperative position shown in dotted lines in Figure 2, to its operative position shown in full lines in that figure. Attention is also directed to the fact that the member 9 is also preferably resiliently connected to the arms 10 thereof, through curved spring-like portions 19 preferably formed integral therewith and with the arms, and that these arms 10 are also slightly resilient laterally, suitable grooves 20 (Fig. 4) or equivalent raised portions being provided on the sides of the outer chuck casing 21 so that these arms may be snapped into position and non-positively locked against accidental displacement when the yoke is lowered to operative position.

In the use of my improved construction, the yoke 9 may, of course, be thrown to its operative position whenever it is desired to operate the drill, the same not interfering with the operation of the steel when the latter is held against the work. However, in service it is usually only moved to operative position when the steel is to be withdrawn or becomes stuck in its hole. It will of course be obvious from the above description that when the steel is thus wedged or stuck in its hole by any means, as for instance, by loose bits of rock or the like catching between the bit and the edge of the hole, the hammer may be made to continue to operate upon the steel, it only being necessary to advance the drill and lower the yoke 9 from its inoperative position shown in dotted lines in Figure 2, to its operative position shown in full lines in that figure, where the yoke is disposed outside but adjacent the front wall of the collar 8, in order thus to limit the forward movement of the steel 6 and thereby retain the rear or inner end of the same within the reach of the hammer 4, so that the latter, by successive blows thereon and through the cooperation of the resiliently mounted yoke, may bring about such a vibration of the steel as to dislodge or crumble the particles retarding the retraction of the steel from the hole. The yoke 9 may then, of course, be returned to its inoperative position and the drilling operation be resumed when desired.

Due to my improved construction, it will be noted that when the steel becomes stuck in the hole, the inner end of the same is retained in operative relation with respect to the hammer, i. e. in such a relation with respect to the hammer that the latter may be made to drive the steel forward and thereby, in cooperation with the resiliently mounted member 9, reciprocate the steel between the limits established by the resiliently mounted member 9 and the front end of

the chuck, in such a manner as to cause a vibration of the steel sufficient to disengage the same from the hole. More specifically, it will be noted that due to the fact that the member 9 is normally out of engagement 70 with the collar on the drill steel, hammer blows are struck both by the hammer and the steel in such a manner as to produce a decided vibration of a character adapted to free the steel. It will also be observed that 75 by this improved construction it is made possible to produce means for performing this new function which are of a rugged character and well adapted to long use in service without breakage. 80

The structure above set out also effects broadly another result, namely, of definitely imparting to the tool a sharply applied striking force in a rearward direction. This result is accomplished due to the fact that 85 upon attempting to remove the tool the transverse portion of the tool retainer will engage the collar 8 so that when the hammer suddenly hits the steel shank, the force and energy thereof will be transmitted to the 90 tool retainer and thereafter immediately returned to the steel in the form of a sharp rearwardly directed driving force, the beneficial effect of which is realized in view of the fact that the hammer is moved, by the 95 air admitted to the front end of the cylinder, away from the steel instantly after the blow is imparted to it.

While I have in this application specifically described one embodiment which my invention may assume in practice, it is of course to be understood that the form shown herein is shown for purposes of illustration, and that the invention may be modified and embodied in other forms without departing 105 from its spirit, it being my intention to include all such modifications within the scope of the appended claims.

What I claim as new and desire to secure by Letters Patent is:

1. A percussive drill including a movable hammer and a chuck, and means carried by said drill and relative to which a steel in said chuck is reciprocable for retaining the inner end of the steel in operative relation 115 with respect to said hammer.
2. A percussive drill including a movable hammer and a chuck, and resilient means carried by said drill and relative to which a steel in said chuck is reciprocable for retaining the inner end of the steel in operative relation with respect to said hammer. 120
3. A percussive drill including a movable hammer and a chuck, and resiliently mounted means carried by said drill and relative to which a steel in said chuck is reciprocable for retaining the inner end of the steel in operative relation with respect to said hammer. 125
4. A percussive drill including a movable

hammer and a chuck, and normally inoperative adjustable means carried by said drill and relative to which a steel in said chuck is reciprocable for retaining the inner end of the steel in operative relation with respect to said hammer.

5. A percussive drill including a movable hammer and a chuck, a drill steel, and means carried by said drill and engageable by said steel after a limited reciprocation thereof in said chuck for retaining the inner end of the same in position to be operated upon by said hammer.

6. A percussive drill including a movable hammer and a chuck, a drill steel, and resiliently mounted means carried by said drill and engageable by said steel after a limited reciprocation thereof in said chuck for retaining the inner end of said steel in position to be operated upon by said hammer.

7. A percussive drill including a hammer and a chuck, and resiliently mounted means for retaining a steel carried in said chuck in operative relation with respect to said hammer and cooperating therewith in vibrating the steel engageable by the steel with a hammer blow after a limited reciprocation of the latter within said chuck.

8. A percussive drill including a hammer and a chuck, and means for retaining the inner end of a steel carried in said chuck in operative relation with respect to said hammer including a resiliently mounted yoke operatively connected to said drill and engageable by the steel with a hammer blow after a limited reciprocation of the latter.

9. A percussive drill including a movable hammer and a chuck, and means for retaining the inner end of a steel carried in said chuck in operative relation with respect to said hammer including a swinging yoke pivoted on said drill and having a resiliently mounted portion engageable by the steel with a hammer blow after a limited reciprocation thereof in said chuck.

10. A percussive drill including a hammer and a chuck, means for retaining the inner end of a steel carried in said chuck in operative relation with respect to said hammer including a resiliently mounted yoke operatively connected to said drill and engageable with a hammer blow by the steel after a limited reciprocation thereof, and means whereby said yoke may be adjusted into a plurality of positions.

11. A percussive drill including a movable hammer and a chuck, means for retaining the inner end of a steel carried in said chuck in operative relation with respect to said hammer including a yoke pivoted on said drill and having a resiliently mounted portion engageable with the steel after a limited reciprocation thereof, and supplementary resilient means resisting movement of said yoke in one direction.

12. A percussive drill including a movable hammer and a chuck, a steel reciprocatively carried in said chuck, and means for retaining said steel within the range of movement of said hammer during the withdrawal of said steel from its hole including a member having a resiliently mounted steel engaging portion engageable with a hammer blow by said steel after a limited reciprocation of the latter in said chuck.

13. A percussive drill including a movable hammer and a chuck, and means for retaining a steel carried in said chuck within the range of movement of said hammer during the withdrawal of the steel from its hole including a member having a steel engaging portion engageable by said steel after a limited reciprocation thereof in said chuck and resilient portions formed integral therewith and operatively connected to said drill.

14. A percussive drill including a hammer piston and a chuck, a plurality of rods on said drill, spring pressed abutments on said rods, and means for retaining the inner end of a steel carried in said chuck in operative relation with respect to said hammer including a yoke member pivotally and slidably mounted on said rods and engageable by said abutments, said member having a resiliently mounted portion engageable with the steel after a limited reciprocation of the latter in said chuck.

15. A percussive drill including a movable hammer and a chuck, means for retaining a steel carried in said chuck within the range of movement of said hammer during the withdrawal of the steel from its hole including a member having a steel engaging portion engageable by said steel after a limited reciprocation thereof in said chuck and resilient portions formed integral therewith and operatively connected to said drill, and co-operating resilient means operating upon said retaining means and normally resisting movement thereof in one direction.

16. For use in combination with a drill formed with a projection adjacent the shank end thereof, a drilling apparatus comprising a percussive motor having a cylinder, a piston reciprocable therein with limited stroke, and a chuck for the retention of a steel, together with a stop cooperating with said chuck and so positioned as to retain said steel with the shank end thereof within the limits of the path of travel of the percussive piston.

17. In combination with a hammer drill having a cylinder, a percussive piston reciprocable in a limited path therein, and a drill steel chuck, a device for removing stuck steels of the type having a projection adjacent the shank end, said device comprising a stop and means for holding said stop in the path of travel of said projection for

impact thereby prior to the movement of said shank out of the limit of travel of the percussive piston.

18. In combination with a percussive drill comprising a cylinder, a piston reciprocating therein, and a chuck, a drill steel having a shank arranged in said chuck for actuation by said piston, said drill steel having a projection to limit its extension into said chuck, and a stop member cooperating with said chuck and with said projection to prevent movement of said steel shank out of the range of movement of said piston.
19. In combination with a percussive drill comprising a cylinder, a piston reciprocating therein, and a chuck, a drill steel having a shank arranged in said chuck for actuation by said piston, said drill steel having a projection to limit its extension into said chuck, and a stop member cooperating with said chuck and with said projection to prevent movement of said steel shank out of the range of movement of said piston, said stop being so located as to permit limited movement of said steel prior to impact of said projection on said stop.

20. In combination with a percussive drill comprising a cylinder, a piston reciprocating therein, and a chuck, a drill steel having a shank arranged in said chuck for actuation by said piston, said drill steel having a projection to limit its extension into said chuck, and a stop member cooperating with said chuck and with said projection to prevent movement of said steel shank out of the range of movement of said piston, said stop having a yoke member supported by an integral spring mounting and having a resilient connection with said drill.

21. A hole forming mechanism comprising a motor having a hammer piston, a tool receiving chuck, a hole forming tool in said chuck, and means relative to which said tool is reciprocable for retaining the inner end of the tool always in operative relation to said piston.

22. A hole forming mechanism comprising a hole forming tool and tool supporting and hammering means comprising a percussive motor whose piston is adapted to percussively actuate the tool, and means forming a guide and support for the tool permitting limited free longitudinal movement of the latter while preventing movement thereof to a point where it will not receive blows from the piston.

23. In combination, hammering means comprising a movable hammer, a hole forming implement percussively actuated by said hammer, and means for supporting and positioning said implement including socket means in which said implement is supported and means operative to be engaged by the

implement after a limited movement thereof in said socket means and to limit the forward movement of said implement in said socket means whereby the same cannot move beyond a position in which it receives the percussive action of said hammer.

24. For use in combination with a hole forming implement provided with means forming an abutment at a point remote from the forward end thereof, a tool supporting and actuating apparatus comprising a percussive motor having a cylinder, a piston reciprocable therein with limited stroke, and means forming a socket within which a portion of such a tool is received together with a stop disposed forward of the rear end of said socket and so positioned as to cooperate with said abutment and retain said tool with its rear end within the limits of the path of travel of the percussive piston.

25. A hole forming mechanism comprising a motor having a hammer piston, a hole forming tool, a tool support permitting the tool and support to have limited free relative movement, said tool being adapted to have relative longitudinal movement in opposite directions in the hole being formed, said elements constituting means whereby a hammering action is imparted to said tool in either direction of said longitudinal movement and independently of the amount of resistance offered to said movement.

26. A hole forming mechanism comprising a motor having a hammer piston, a hole forming tool, a tool support permitting the tool and support to have limited free relative movement, said tool being adapted to have relative longitudinal movement in opposite directions in the hole being formed, said elements constituting means whereby hammering action is imparted to said tool while the same is moving relatively into and out of a hole, said action being independent of the amount of resistance offered to removal.

27. A hole forming mechanism comprising a motor having a cylinder, a hammer piston therein, a hole forming tool, a tool support permitting the tool and support to have limited free relative movement, said tool being adapted to have relative longitudinal movement in opposite directions in the hole being formed, said elements constituting means whereby hammering action is imparted to said steel to form a hole on the moving of said cylinder in a forward direction relative to said hole and whereby a hammering action is also imparted to said tool when said cylinder is relatively reversely moved, said action being independent of the amount of resistance offered to said reverse movement.

In testimony whereof I affix my signature.
GEORGE H. GILMAN.
